PACKAGE CONVEYING AND DISTRIBUTING DEVICE

Filed Dec. 15, 1916

2 Sheets-Sheet 2

Witness:

UNITED STATES PATENT OFFICE.

SAMUEL OLSON, OF CHICAGO, ILLINOIS.

PACKAGE CONVEYING AND DISTRIBUTING DEVICE.

Application filed December 15, 1916. Serial No. 137,086.

To all whom it may concern:

Be it known that I, SAMUEL OLSON, a citizen of the United States, residing at Chicago, in the county of Cook and State of Illinois, have invented new and useful Improvements in Package Conveying and Distributing Devices, of which the following is a specification, reference being had to the accompanying drawings, forming a part thereof.

This invention relates to conveying and distributing mechanisms and associated devices designed for saving time and labor in the handling of packages. The present invention is particularly well adapted to be installed in a room or passage where the head room is limited, in that a part of the device may be suspended from the ceiling making a very light, easily installed and economical structure.

Other features and advantages will be readily recognizable as described and shown in the drawings and as indicated by the claims.

25 In the drawings:—

Figure 1 is a diagrammatic side elevation showing the relative arrangement of the several elements embodying this invention.

Figure 2 is a side elevation of the tripper. 30 Figure 3 is a transverse vertical section taken on line 3—3 of Figure 2 as to the tripper, the remainder being a typical transverse vertical section of the receiving tables.

The associated devices embodying this invention are shown as applied between a loading or feeding room or point as at A. and a receiving and distributing room, showing the conveyer belt, 1, extending along between the receiving tables, 2, 2^a, which may be of any desired or convenient length. The belt is arranged to run as is usual over a driving or head pulley, 3, and a take-up pulley, 4, the usual supporting rollers, 5, 5, being placed at intervals to prevent sagging thereof.

45 For depositing the packages at any desired point of the receiving tables, 2, 2^a, there is provided a tripper or belt-unloading device, 10, which consists of a "trip" pulley, 11, and an idler pulley, 12, located below and a short 50 distance back of the pulley, 11. The upper pulley of the belt, 1, carrying the packages is arranged to run over the said pulley, 11, which pulley, as seen in Figure 2, causes it

to travel in an upwardly inclined direction between the vertical side guard plates, 13^a, 55 to a point of sufficient height to deliver the packages carried thereby upon an inclined apron, 13^c, located between the pulley, 11, and a spreading or dividing structure comprising the two sloping or inclined plates, 13, 60 13^a, whose meeting edges form a ridge, 13^b, lying in a horizontal plane and in a direction parallel with the center line of the conveyor belt. The packages will then descend toward the receiving tables changing their direction of travel substantially ninety degrees 65 from their original course.

The tripper is arranged to deliver packages at any desired point intermediate its termini or to deliver while traveling in 70 either direction, and it is provided with a motor, 30, for propelling it which is controlled by a direction-controlling device, 31, whose operating arm or lever, 32, projects therefrom and encounters tappets, 33 and 75 34, fixedly mounted and so located at opposite ends of the range of travel of the tripper truck as to perform the reversing function automatically.

It is manifest that devices similar to the 80 tappets, 33 and 34, can be placed at any desired point or points intermediate the termini for encounter with the operating or reversing lever, 32, and that they may be rendered inoperative at will; each of the tappets it will be noted is of bell-crank form 85 and so mounted that it is restricted in its possible swing to 90 degrees and when the lever, 32, approaches its vertically depending portion from the side opposite its horizontally extending leg it will operate as a rigid member and cause the said lever to reverse the motor, the lever having sufficient elasticity in its mounting to snap back in 90 position after engagement with the tappets 95 to be subsequently encountered. If, however, the lever approaches from the opposite side, that is, first passing under the horizontally extending leg, the vertical leg will offer no resistance and will not operate the lever but will itself be swung about on its pivot. It will be understood that there may be sufficient frictional resistance in the mounting of the tappet to hold it in position 100 for proper operation.

105 The purpose of interposing these tappets

is so that the conveyor may serve any portion of the length of the table when the entire length thereof is not required, as for instance, when the conveyor is operating at 5 less than full capacity.

The device 31, being no part of this invention, the specific structure thereof need not be here described further than to point out that it is of the nature of a reversing 10 switch for the motor and its design and effect is generally known and understood.

It is not desirable for the packages to be deposited directly upon the horizontal receiving tables, because the obviously consequential accumulation thereof would tend to congest the service as by blocking the path of travel of the tripper, resulting in a possible injury to the packages, therefore the tables are placed at suitable distances 15 from such path and slightly lower than the inclined aprons or plates, 13, 13^a, of the tripper and the distance or gap is bridged by stationary inclines, 14, 14^a, extending the full length of the tables, the acclivity of 20 these connecting members being approximately half that of the aprons, 13, 13^a, and it is evident that their purpose and use is first to retard the travel breaking the fall and to finally deposit the packages clear 25 of the path of the tripper thus providing the last of a series of inclines of decreasing abruptness. It will be noted that the lower edge of the aprons, 13, 13^a, are arranged to overhang the upper edges of the bridges, 14, 30 14^a, thus providing an uninterrupted runway, precluding the possibility of the packages being snagged on their descent. The outer sides of the tables are provided with 35 guard rails or plates, 15, 15^a, of any suitable height. The structure supporting the tables is composed of very light angle-iron sections as seen in Figure 3, the members, 20, extending entirely across, tying and spacing all the posts, 21, 22, 23, 24, 25 and 26. 40 The posts, 25 and 26, are of sufficient height to support the cross members, 27, and secure the longitudinal members, 28, 28^a, 29 and 29^a. The upper edges of the bridges, 14, 14^a, rest on the members, 28, 28^a, 45 where the tripper plates 13, 13^a, overlap them, and their lower edges are fitted to the tables, 2, 2^a, in a smooth juncture therewith. 50

Since the nature of the tables and their intended purpose admit of a very light structure, it is found economical to support the associated tripper entirely independently therefrom. Any conceivable support for the tripper from the floor in the present design would be a waste of material and a possible hindrance to the travel of the belt or of a desirable relative arrangement of the members, 13, and 14, as at 14^b; and since it is recognized that a member in tension is more economical than one in compression, it 55 is found desirable and convenient to sus-

pend the traveling tripper from the ceiling, thus producing tension in its main members with the consequent economy in material.

The track members, 40, 40^a, clearly seen in Figure 3 are secured to the ceiling and 70 suitably braced by brackets, 41, 41^a. The said track members are preferably made of "channel sections" which provide means for guiding and guarding the wheels, 42, 43 and 44. The tripper is further guarded 75 from lateral swaying by the rollers, 29^b and 29^c, which run on the inside of the vertical flange of the members, 29, 29^a.

Associated with the wheels are the shafts, 45, 46 and 47 journaled in suitable fittings, 80 50, to which are attached the pairs of vertical members, 52, 53, 54, and 55 at the lower ends of which are attached the horizontal members, 56. The transverse members, 57, 58, 59 and 60 support the longitudinal members, 56^a, 56^c, and 61. 85

The motor, 30, mounted on the bracket, 62, drives the shaft, 45, by means of the chain, 63, and sprocket wheels, 64 and 65, on the motor shaft and the truck shaft, 45, 90 respectively.

The tripper pulley, 11, carried on the shaft, 11^a, is journaled in the bearing-boxes, 12^b and 12^c, and secured to the members, 56—56.

It will be understood that the usual provision for the handling of packages after they are delivered or distributed on the tables is that clerks are stationed along the 100 tables at proper and convenient points in sufficient numbers to fully develop the efficiency of the system.

Figure 2 shows conventionally a manually operable controller, 70, for the motor, 30, and a cable of electrical conductors, 71, which may be understood as leading from said controller to said motor. It will be evident that if desired, the tripper may thus be manually controlled to operate at various speeds for distributing packages as desired and may be operated over any part of the length of the receiving tables, 2 and 2^a, if so restricted.

I claim:—

1. In combination with an elongated work table, means for distributing packages thereto, comprising a conveyor belt traveling parallel to said table, and a tripper, comprising a truck mounted to travel longitudinally of the belt and having a loose pulley over which the belt is fed for discharging its load, a laterally-discharging inclined plate on the truck in position to receive such load from the belt and deliver it to the table, said table being laterally spaced from the conveyor belt clear of the path of the tripper, with a longitudinally extended platform bridging such space and sloping downwardly from the side of such path to the table, a second pulley over which 115 120 125 130 135

the belt is fed from the first and out forwardly from the tripper truck, and means for moving such tripper back and forth over the path of the belt at will, or arresting it 5 at any point in such travel for distributing the material discharged from its plate over the table.

2. In combination with an elongated work 10 table, means for distributing packages thereto, comprising a conveyor belt traveling parallel to said table, and a tripper comprising a self-propelled truck mounted for travel longitudinally of the belt and having loose pulleys over which the said conveyor 15 belt is arranged to run, one of said pulleys arranged to cause the belt to discharge its load, a laterally-discharging inclined plate on the truck arranged to receive such load from the belt and deliver it toward the

table, said table being laterally spaced from 20 said conveyor belt, and the path of said tripper, and a longitudinally-extending inclined platform bridging such space and sloping downwardly from the side of such path to the table, at an angle approximately 25 half that of the laterally inclined plate of the truck.

3. In the combination defined in claim 1, 30 means for automatically reversing the direction of travel of the truck.

4. In the combination defined in claim 1, automatic means for limiting the travel of the truck within any desired part of its total possible range.

In testimony whereof, I have hereunto 35 set my hand at Chicago, Illinois, this 7th day of December, 1916.

SAMUEL OLSON.
